UNITED STATES PATENT OFFICE.

WILLIAM H. CLOUD, OF DETROIT, MICHIGAN, ASSIGNOR, BY MESNE ASSIGNMENTS, TO THE CLOUD MANUFACTURING COMPANY, OF MICHIGAN.

PUMP.

SPECIFICATION forming part of Letters Patent No. 256,126, dated April 11, 1882.

Application filed August 17, 1881. (No model.)

To all whom it may concern:

Be it known that I, WILLIAM H. CLOUD, of Detroit, county of Wayne, State of Michigan, have invented a new and useful Improvement 5 in Pumps; and I declare the following to be a full, clear, and exact description of the same, such as will enable others skilled in the art to which it pertains to make and use it, reference being had to the accompanying drawings, which 10 form a part of this specification.

My invention consists of the combinations of devices and appliances hereinafter set forth, and more particularly pointed out in the claims.

In the drawings, Figure 1 is a longitudinal 15 section of a well, showing my device in position. Fig. 2 is a separate sectional view of the pump. Fig. 3 is a separate view, illustrating my outlet-valve mechanism and spring.

This invention is designed as an improvement 20 upon the pump patented to me February 22, 1881, No. 230,026.

My improvement consists, first, in the combination, with the plunger-rod of a double-acting pump, of a pivoted cross-bar, from the pivotal point of which depends a rigidly-attached 25 pendulum-lever, a similar pivoted cross-bar nearer the pump, and having one end connected with the plunger-rod, and rods connecting the ends of the two pivoted cross-bars, so that each 30 may turn on its pivot. By vibrating the pendulum-lever the outer cross-bar is caused to pull alternately upon the rods connecting its ends to the inner cross-bar, and an equal force 35 may be conveniently exerted by hand for operating the plunger-rod in both directions.

The invention consists, secondly, in the combination, with the pendulum-lever, of a handle pivoted to its lower end, and provided with a weight at one end for causing said handle to 40 stand in a vertical position when not in use, as will be hereinafter fully described.

It consists, thirdly, in the combination, with the two outlet-valves of a double-acting pump, of a single strip-spring confined at its middle 45 portion, and having its opposite ends bearing upon said valves, respectively, to hold them closed. By this construction I decrease the number of separate parts and lessen the manipulation necessary in setting up and taking 50 apart the pump.

The invention consists, also, in a novel manner of supporting the spring in position to act properly upon the valves.

In carrying out my invention, A represents a pump cylinder or case divided by a close partition, A', through which passes with a close fit the cylindrical plunger B.

C represents inwardly-opening valves, which I term the "inlet-valves." A stem or stems, C', project out through the case, and upon the exterior are provided with spiral springs C², which serve to hold the valves snugly upon their seats when closed, but permit them to yield whenever a vacuum is produced within by movement of the plunger.

D represents the outlet-valves.

D' is a bridge, and D² a strip-spring resting across and secured to the bridge, so that one of its ends will bear upon one of the valves and the other end upon the other valve, so as by 70 its retraction to hold the valves snugly upon their seats when closed. I find the employment of a valve-spring in these cases to be of great advantage, since it prevents any leakage back from the discharge-pipe into the space 75 back of the plunger as it is moving forward. I also deem the construction which enables me to use a single spring to govern both valves as very advantageous in the matter of simplicity and economy of structure.

E is the base-plate, which forms the lower end of the pump-chamber, and is provided with legs, by which the structure may be secured to a board located in the bottom of the well or cistern, yet be raised sufficiently high to enable 85 the pump to take its water directly through the bottom of the chamber. This construction is of value, inasmuch as it raises the pump high enough to avoid danger of drawing in sediment or grit from the bottom of the well, and makes 90 a cheap and substantial structure.

F is a cap which covers the outlet-valves and constitutes the base of the discharge-conduit. It can be readily removed to afford access to the valves.

F' is the discharge-conduit. It is supported above the top of the well by legs G, which all connect with a single clamp, G'. This clamp also is provided with a pintle, upon which swings the pendulum-lever H. This lever is 100

provided at its upper end with a cross-bar, H' , which is rigidly secured thereto.

5 I is a rod or strap, which may extend down and be connected directly with the pump-shaft B' , and thus communicate motion to the plunger B as the pendulum is swung to and fro. I prefer, however, to provide another pivoted cross-bar, H^2 , preferably near the pump-chamber, and connect the respective ends of the said 10 cross-bars with each other by straps or rods I I' , which, if the well is deep, may be stayed at one or more intermediate points by stay braces or guides I^2 , through which the rods or straps may loosely pass, and thus be steadied. By 15 employing the two cross-pieces H' and H^2 the strains upon the rods I and I' are always strains of extension. They do not therefore have to be so stiff and strong as would be required if they were obliged, as in the case of a single 20 rod, to sustain alternately a pull and a thrust. The rods may be secured to the cross-pieces either by rivets or by bolts, as may be desired.

25 J is a handle pivoted to the lower end of the pendulum-lever, by which the same can be readily operated, and I prefer to provide a counterpoise-weight, J' , at the opposite sides of the pivot, which shall be sufficiently heavy to lift the handle to a vertical position when it is not in use. By this means the handle is 30 always in the best place for convenience, and yet is always up out of the way when not in use.

35 K is an air-chamber, which, if closed, puts the apparatus in condition for use as a force-pump by which to throw water to a distance— as, for instance, through a hose; but when open it simply serves to give a little head to the water above the discharge-point, thus causing it to discharge with a regular stream.

40 The plunger B may, if desired, be made hollow and be filled with a wooden plug, thus reducing its weight; or, instead of filling it with wood, it may simply be cast hollow, but closed at all points but its point of attachment to the pump-shaft B' , thus accomplishing the same 45 end.

Instead of a rigid slotted stay, I^2 , there may be, if desired, located at this point simply an intermediate pivoted bar, like the bar H^2 , the ends of which may be connected with the straps I and I' .

50

55 L is a shelf, attached in any suitable manner to the pump; but I prefer to attach it by means of a clamp, L' , for the reception of a vessel. This shelf is perforated, that water may not be retained on it, and I also prefer to make it a swinging shelf, that it may be out of the way when not in use.

What I claim is—

1. The combination, with the plunger-rod of a double-acting pump, of the upper pivoted 60 cross-bar, having the pendulum-lever rigidly secured to its pivotal portion, the lower pivoted cross-bar, having one end connected with the plunger-rod, and the rods connecting the ends of said pivoted cross-bars, substantially 65 as described.

2. The combination, with the pendulum-lever, of a handle pivoted to its lower end and provided with a counterpoise-weight for causing the handle to stand vertical when not in 70 use, substantially as described.

3. The combination, with the two outlet-valves, of the single strip-spring confined at its middle portion, and having its opposite ends bearing upon said valves, respectively, to 75 hold them closed, substantially as described.

4. The combination, with the two outlet-valves of a double-acting pump and the intermediate bridge, D' , of the flat strip-spring D^2 , having its middle portion secured to said 80 bridge and its opposite ends bearing upon said valves to hold them normally closed, substantially as described.

In testimony whereof I sign this specification in the presence of two witnesses.

WILLIAM H. CLOUD.
